INTERNAL COMBUSTION ENGINE

Walter R. Griswold, Detroit, Mich., assignor to
 Packard Motor Car Company, Detroit, Mich., a
 corporation of Michigan

Application July 22, 1933, Serial No. 681,685

33 Claims. (Cl. 123—90)

This invention relates to internal combustion engines and particularly to the valve operating mechanism thereof.

Automobile engineers are constantly striving to eliminate noise from the various mechanisms of the motor vehicle. One of the most troublesome parts of the vehicle in this respect is the valve mechanism of the engine, principally because of the expansion and contraction of the parts of the engine in connection with which the valve mechanism is mounted, and partly because of the wear that necessarily takes place in the operation of the parts.

The conventional valve mechanism includes a 15 poppet valve and a cam shaft for operating it. When the valve is closed there is preferably very slight clearance somewhere between the cam shaft and the valve stem, or at least there should be no "riding" of the valve stem on the cam shaft because in that case the valve 20 would not be fully closed. A leaky valve would soon burn or there would be a loss of power due to lack of compression.

But if there is too much clearance the valve 25 operating mechanism will be noisy due to the clearance being taken up suddenly.

In most engines there is provision for adjustment between the cam shaft and the valve stem so that a minimum of clearance may be 30 provided for, but when this adjustment is made at a given temperature of the engine the clearance will increase or decrease as the engine becomes hotter or cooler and then a noisy mechanism results or the valves will be caused to ride.

In some cases elaborate mechanisms have been 35 provided for automatically taking up this valve mechanism clearance without at the same time causing the valves to ride, and the present invention is concerned with this problem. One 40 of its objects is to provide such automatic take-up mechanism in simple form, in compact arrangement, easily assembled, easily accessible, and with the thought of insuring automatic adjustment over a fairly wide range.

Another object of the invention is to provide 45 a valve operating mechanism of this character which will not only adjust the clearance between the cam shaft and the valve but in which the operating part between the cam shaft and the 50 valve will readily adapt itself to the cam surface.

Another object of the invention is to so design 55 the various parts of the mechanism that in commercial manufacture several parts may be separately assembled into what may be termed "sub-

assemblies" and then the whole brought together for convenient assembly on the engine itself with the parts in accessible position for inspection and adjustment.

Another object of the invention is to provide 5 in a mechanism of this character for the arrangement of the regulator or adjusting mechanism on the stationary part of the engine where it may be easily inspected in operation and accessible for adjustment or removal and replacement. 10

Another object of the invention is to provide 15 automatic adjusting mechanism for valve operating elements with means for dampening vibrations occurring therein.

Other objects of the invention will appear from 20 the following description taken in connection with the drawings, which form a part of this specification, and in which:

Fig. 1 is a vertical sectional view of an engine 25 having valve operating mechanism embodying the invention;

Fig. 2 is a sectional view taken on line 2—2 of Fig. 3 further illustrating the valve operating mechanism shown in Fig. 1;

Fig. 3 is a fragmentary sectional view of the 25 same taken on line 3—3 of Fig. 2;

Fig. 4 is a sectional view on line 4—4 of Fig. 3;

Fig. 5 is a perspective view of one of the cam 30 regulator structures which controls the position of the rocker lever fulcrum;

Fig. 6 is a sectional view taken on line 6—6 of Fig. 1, illustrating the aligned relation of the bearing points for the rocker lever;

Fig. 7 is a view similar to Fig. 2, showing 35 another form of the invention, the section being on the line 7—7 of Fig. 8;

Fig. 8 is a sectional view substantially on the line 8—8 of Fig. 7, and

Fig. 9 is a perspective view of the support for 40 the regulating mechanism, shown in Figs. 7 and 8.

Referring to the drawings, 10 represents the 45 crank case of an internal combustion engine upon which is secured a cylinder block 11 having a head block 12 mounted thereon. Within each cylinder is a piston 13 which is connected by a rod 14 with the crank shaft 15.

As the cylinders and associated mechanisms 50 are similar, a description of one of the units will suffice for all. The head block is formed with a chamber 16 which overlies an end portion of the cylinder and communicates with a passage 17 in the cylinder casting. The passage 17 may be for either the inlet or the exhaust. A valve 18 55

is provided with a stem portion arranged to be reciprocated in a bearing sleeve 19 carried by the cylinder casting and the head portion of the valve is arranged to open or close the port between the chamber 16 and the passage 17. One end of a coil spring 20 engages the cylinder casting and the other end thereof bears against a retainer 21 which is fixed to the valve stem in the usual manner. A tappet 22 is slidably mounted in a bearing 23 extending through a wall of the crank case, such tappet forming a continuation of the valve stem. The valve stem and its associated tappet may be referred to herein as the valve.

15 A cam shaft 24 extends longitudinally of the crank case and, in this instance, is arranged below the valves and at one side thereof. A rocker arm or lever 25 is arranged between the valve and a cam 9 on the cam shaft, an end of the 20 rocker lever being formed with a bearing face 26 for engaging the valve and having a bearing roller 27 mounted thereon for engagement with the cam 9 on the cam shaft.

The structure so far described is of conventional character and commonly employed in engines of the four cycle type.

In order that the regulating mechanism for the rocker lever of the valve operating mechanism can be economically manufactured and serviced, I propose to associate the same in a unitary structure which can be readily attached to and removed from the engine and I also propose to arrange the regulator mechanism in a relation whereby it is readily accessible either 35 when the unit structure is attached to or removed from the engine. To this end, the rocker levers are arranged to extend through an opening 28 in a side wall of the crank case so that the journaled or fulcrumed portion thereof can 40 be carried in a housing 29 which is detachably secured against the outer wall of the crank case by means of suitable studs or bolts 29'. The housing is formed with a pair of spaced walls 30 and 31, the upper one of which has upstanding bearing brackets 32 to support a shaft 33 which extends longitudinally of the engine. A removable cover 34 encloses the shaft and its bearing brackets, such cover being retained in position by bolts 35 which extend into the brackets and engage recesses 36' in the shaft to prevent endwise movement thereof.

The rocker lever 25 is fulcrumed upon a bearing member 36 which in turn is carried by a carrier 37 which is shown in the form of a cylindrical pin passing diametrically through an opening in the bearing member 36. The lower portion 38 of the carrier pin 37 is of less diameter than the upper portion 39 thereof, thus forming a shoulder 40 which bears against the bearing member 36, as shown particularly in Fig. 2. The hub 41 of the rocker lever 25 surrounds the bearing member 36 and is provided with slots 42 and 43 through which the pin 37 passes and which permit the rocker lever to rock on the bearing member 36 in the operation of the mechanism. The upper end 39 of the pin 37 has flat sides 44 which bear against the side faces of the slot 43, thus providing a greater bearing surface between the rocker lever and the pin.

70 The carrier pin 37 is mounted in the housing 29 in openings 45 and 46 therein, and the lower end of the pin is provided with a flat face 47 to permit oil to escape from the bottom of the recess formed by the opening 45.

75 Thus it will be seen that the rocker lever or

rocker levers are carried by the housing 29 and they may be assembled in the housing and then the housing and the rocker levers may be assembled on the engine as a unit. For the purpose of holding the rocker levers against undue turning in the housing before assembly on the engine, each of the rocker levers 25 is provided with a lug 48 extending from the hub 41 and adapted to operate between separated ribs 49 formed in the housing. Sufficient clearance is provided between the lug 48 and the adjacent ribs so that the rocker levers will have slight movement about the axis of the pin 37 for the purpose of permitting the rocker lever to properly position itself relative to the cam shaft.

Therefore, since the rocker lever 25 is supported in the housing 29 on the axis of the pin 37, and since the roller 27 and the bearing face 26 are aligned with the carrier pin 37, the roller will automatically find its bearing on the cam face and there will be no binding or uneven wearing of the roller or cam.

In the form of the invention shown in Figs. 1 to 6 inclusive, the carrier 37 is so supported that in the operation of the mechanism the carrier will be moved laterally or vibrated so that it may co-operate with the regulating or adjusting mechanism which positions it axially in its support. Thus the carrier pin 37 is mounted in the housing 29 not only for axial movement in the openings 45 and 46 but also for slight lateral movement therein. Thus, as indicated on the drawings in Fig. 2, there is diametral clearance of from two to five thousandths of an inch between the cylindrical surfaces of the portions 38 and 39 of the pin 37 and the openings or recesses 45, 46, respectively, of the housing. This is more than enough clearance for the normal axial movement of the pin for adjustment of the fulcrum of the rocker lever 25, so that when the cam 9 of the cam shaft 24 reaches a position where it starts to raise the rocker lever 25, it also tends to move the lever endwise or towards the left in Fig. 2 and this moves the pin 37 laterally so that the clearance is all on the right hand side thereof. Then as the roller 27 rolls down the other side of the cam 9, under urging of the valve spring 20, the rocker lever 25 is urged toward the right in Fig. 2 and the pin 37 is moved slightly to the right so that all of the clearance is then on the left hand side of the pin. In the rapid rotation of the cam shaft 24 this sets up a lateral vibration of the pin 37 and facilitates the operation of the regulating mechanism.

The regulating or adjusting mechanism for the fulcrum of the rocker lever 25 is mounted on a stationary part of the engine and as shown, it is supported on the shaft 33 which is mounted in the brackets 32 of the housing 29. This regulating mechanism may be assembled separately and the assembly is then threaded on to the shaft 33. Two of these mechanisms are shown in Fig. 3, one on either side of the bracket 32. They are alike except that they are reversed relative to the bracket 32.

As assembled in place on the shaft 33 the regulating or adjusting mechanism comprises a cam 55 adapted to rotate on the shaft 33 immediately above the pin 37. Its periphery is in contact with the upper end of the pin which carries the rocker arm, so that the direction of vibrating movement of the contacting surface of the pin, is tangent to the surface of the cam. The cam is shown as slightly offset relative to the center of

the pin, however, it can be centrally located if desired. The periphery of this cam is preferably of involute form as shown particularly in Figs. 1 and 2 so that its rotation in one direction on the shaft will tend to push the pin 37 downwardly in Fig. 2 and its rotation in the reverse direction will permit the pin to move upwardly under pressure of the valve spring 20.

A stamped metal casing 56, of cylindrical form, 10 and having its outer end opened and its inner end partly closed by a flange 58, is secured in somewhat offset relation to the side of the cam 55. The offset is obtained by a portion of the flange 58 being extended as shown at 59 and 15 formed with a lip 60 which is the part of the casing riveted or fixed to the cam as by the rivets 57.

Within the cylindrical casing 56 and keyed upon the shaft 33 is a sleeve 61. At one end this sleeve abuts against the bracket 32 and at the 20 other end against the cam 55. A spring 62 surrounds the shaft 33 on the opposite side of the cam 55 and a cotter pin 63 extends through the shaft and retains the spring 62 in somewhat compressed condition against the cam, thus holding 25 the parts in place and damping any lateral vibrating action of the cam.

Coiled about a portion of the sleeve 61 and within the casing 56 is a spring 64 having one of its ends secured in a slot in the sleeve 61 as 30 shown at 65 and its other end secured in a slot in the casing 56 as shown at 66, particularly in Fig. 5. The spring is wound under tension so that it tends to rotate the cam 55 on its axis, the sleeve 61 being keyed to the shaft 33 which is 35 prevented from turning by reason of the bolt 35.

This tendency of the cam 55 to rotate is in a clockwise direction in Fig. 2 so that the cam tends to push the carrier pin 37 downwardly and thus tends to take up clearance between the cam 40 shaft 24 and the engine valve. In case the clearance has been taken up to such an extent that there is a tendency on the part of the engine valve to "ride", the valve spring 20 will tend to push the carrier pin 37 upwardly with considerable force and this will be resisted by the cam 55. To prevent this riding action the retraction of the cam 55 is necessary and this is facilitated by the vibratory action of the pin 37 45 in a direction tangent to the cam 55 as above pointed out. Thus, with each rotation of the cam shaft 24 the upper end of the pin 37 is moved laterally from one side to the other and back again, taking up the clearance between it and its support, first on one side and then on the 50 other. It is this relative movement between the cam 55 and that part of the pin 37 with which it contacts that accomplishes the retraction of the cam against its spring 64 under these conditions.

60 It should be pointed out that the spring 64 is in the form of a flat watch spring and only two or three coils are illustrated. This is a desirable form of spring but in practice six or eight coils are used, the lesser number of coils being illustrated in order to make the showing clearer.

65 For assembling the regulator off of the shaft 33 the sleeve 61 is made to loosely fit within the flange 58 of the casing and it is formed with a flange 67 intermediate its ends, which flange 67 70 is extended radially at one point to form an arm 68 which, when the sleeve 61 is arranged within the flange 58, will extend slightly beyond the extension 59 of the casing 56. The arm 68 and the extension 59 thereby form a stop means to limit 75 relative rotation of the sleeve 61 relative to the

cam 55 and housing 56, in both directions. In Fig. 5 the arm 68 is shown as resting against the extension 59, and in Fig. 4 the arm 68 is shown in full lines in its intermediate position in which the sleeve is operative relative to the cam 55, and in dotted lines in its two extreme positions resting against the extension 59.

The extension 59 of the casing 56 is preferably formed by punching out a part of the flange 58 and this forms an opening through that flange through which the sleeve 61 may be assembled with its flange 67 and arm 68 arranged between the flange 58 and the cam 55. Thus the parts may be assembled as shown in Fig. 5 with the cam 55, its integral casing 56, the sleeve 61, and the spring 64 assembled with relation to each other. This assembly may be threaded onto the shaft 33 with the open end of the casing 56 adjacent the bracket 32 whereby the latter retains the spring within the casing, and with the spring 62 yielding- 20 ly holding the parts in place.

In the form of the invention shown in Figs. 7, 8 and 9 the crank case 10, its opening 28, the valve means 22, the rocker lever 25, its roller 27, the bearing member 36, the lug 48 and ribs 49 25 may be the same as in the other construction. The housing 29 is substantially the same except that the upper part thereof is formed with an opening 70 through which the openings 45' and 46' may be drilled, a cover 71 being provided for the opening 70, and except for an extension 72 which may be said to replace the brackets 32 of the other construction. The extension 72 is formed with an opening 73 through which the regulator assembly is assembled within the housing, and a cover 74 forms a support for the regulator mechanism, being secured in place by bolts 75. A single cover is shown as supporting two of the operating mechanisms but it may support 30 or less of them. 40

In this form of the invention the relative vibration between the carrier pin 37 and the cam 55 is attained, not by providing clearance between the pin 37 and its support, but by slight oscillation of the pin 37 during the operation of the mechanism and by offsetting the cam 55 to a greater extent than shown in the other form. Thus the clearance at 45' and 46' in this construction, is enough only to insure free axial movement 45 of the pin 37 in its adjusting or regulating operation, and the pin itself is oscillated slightly by the rotation of the cam shaft 24. This oscillation of the pin may be accomplished in any desirable way but as herein shown the cylindrical segment of the cam 9, upon which the roller 27 operates, is formed with waves 76, (shown greatly exaggerated for clearness), as shown in Fig. 7, so that as the roller 27 follows the cam shaft there is a tendency for it to move first to one side and then to the other, of the cam, and of course carrying with it the free end of the lever 25. This lateral movement of the rocker lever 25 gives the pin 37 a slight oscillating movement. The cam 55 is shown as offset relative to the axis of the pin 37 and consequently this oscillating movement of the pin causes a tangential relative movement between the upper enlarged end 77 of the pin and the cam 55. This relative movement facilitates retraction of the cam against its spring when there is a tendency of the engine valve to ride, as above pointed out. 50

The regulating mechanism is the same in all particulars as that shown in the other form, but its supporting shaft 33' is arranged laterally of the cam shaft 24, instead of parallel thereto, and 75

is supported in the cover 14. In this case there are individual shafts 33' for each regulating mechanism but two or more of these shafts may be mounted on the cover 14, as shown particularly in Figs. 8 and 9.

The operation of the regulating mechanism in its co-operation with the fulcrum of the rocker lever 25 is the same as that of the other form of the invention and a description thereof need not be repeated here.

It will be understood that various forms of the invention other than those described above may be used without departing from the spirit or scope of the invention.

15 What I claim and desire to secure by Letters Patent is:

1. In a valve operating mechanism, the combination of a valve operating member, a support therefor to provide for its normal rocking action in operating the valve, means provided for additional vibratory action of said member during operation, and a spring actuated cam device directly pivoted upon said support for adjusting the position of said member to take up clearance, said vibratory action assisting in the operation of said cam device.

2. A take-up mechanism including a shaft, a cam rotatably mounted on said shaft, a sleeve mounted upon and keyed to said shaft adjacent 30 said cam, a coil spring having one end connected to the cam and the other end connected to the sleeve, and stop means between the parts to limit the relative rotary movement in both directions between the cam and the sleeve, said cam, sleeve and spring being self-contained for assembly upon or disassembly from said shaft.

3. A take-up mechanism including a shaft, a cam element on the shaft, a second element on the shaft, a coil spring connecting said elements 40 tending to turn one relative to the other, stop means between the elements to limit the range of relative rotary movement between them, and means for securing one of said elements against rotation on the shaft, said elements and springs 45 being adapted for assembly upon and disassembly from said shaft as a unit.

4. A take-up mechanism including a shaft, a cam element on the shaft, a second element on the shaft, a coil spring connecting said elements 50 tending to turn one relative to the other, stop means between the elements to limit the range of relative rotary movement between them, and means for securing one of said elements against rotation on the shaft, said elements and spring 55 being adapted for assembly upon and disassembly from said shaft as a unit, and said stop means retaining the elements against undue relative movement when the unit is disassembled from the shaft.

60 5. In a valve operating mechanism, the combination of supporting means, a rocker arm mounted in said supporting means so that it may rock in operating the valve and so that it may have slight movement lengthwise, and a cam device mounted directly on the supporting means and acting against said rocker arm to adjust the rocker arm for clearance take-up.

6. In a valve operating mechanism, the combination of a rocker arm, a bearing member therefor, a carrier passing laterally through the bearing member, and a cam member mounted independently of said carrier and operating directly against said carrier to move the latter to thereby 70 adjust the axis of the bearing member, for the purpose set forth.

7. In a valve operating mechanism, the combination of a part to be adjusted for clearance take-up, and a regulator therefor comprising a supporting shaft, a cam rotatable on the shaft, a part keyed to the shaft, and a coil spring having one end connected to said cam and the other end connected to the part keyed to the shaft.

8. In a valve operating mechanism, the combination of a cam shaft, a valve, a rocker arm adapted to be rocked by the cam shaft and to operate the valve when so rocked, and means for supporting the rocker arm so that it may move laterally to find its correct operating position on the cam shaft.

9. In a valve operating mechanism, the combination of a cam shaft, a valve, a rocker arm adapted to be rocked by the cam shaft and to operate the valve when so rocked, means for supporting the rocker arm so that it may move laterally to find its correct operating position on the cam shaft, and means for limiting said lateral movement.

10. In a valve operating mechanism, the combination of a cam shaft, a valve, a rocker arm adapted to be rocked by the cam shaft and to operate the valve when so rocked, and means for supporting the rocker arm comprising a bearing member, and a pin extending laterally through the bearing member.

11. In a valve operating mechanism, the combination of a cam shaft, a valve, a rocker arm adapted to be rocked by the cam shaft and to operate the valve when so rocked, and means for supporting the rocker arm comprising a bearing member, and a pin extending through the bearing member for permitting limited lateral movement of the rocker arm, for the purpose described.

12. In a valve take-up mechanism, the combination of a valve operating part adjustably mounted to take up clearance, a cam part mounted on a stationary support and adapted to adjust said valve operating part, one of said parts being so mounted as to vibrate slightly during operation in addition to its normal functional movement, and a spring for operating said cam part in co-operation with said vibratory movement.

13. Valve operating mechanism comprising a rocker lever, a bearing on which the rocker lever is mounted, a movable carrier means, means for automatically regulating the position of the carrier including an involute cam engaging with the carrier means, and vibration damping means associated with the cam.

14. Valve operating mechanism having a rocker lever with shiftable fulcrum means, regulator mechanism for the fulcrum means comprising a fixed shaft, a sleeve fixed on the shaft, an involute cam rotatable on the shaft engageable with the fulcrum means, spring means between the sleeve and the cam urging the cam into wedging relation with the fulcrum means, and a coil spring on the shaft bearing against said cam, said coil spring damping vibration of the cam.

15. In an engine, a casing having walls spaced vertically, rocker lever fulcrum means between the walls, a carrier for the fulcrum means slidably mounted in the walls, said carrier projecting beyond the upper wall, regulator means carried by the casing above the upper wall and engaging the carrier to automatically maintain it in adjusted position, and a removable cover on the casing extending over the upper wall and

enclosing the regulating means and the ends of the carriers projecting beyond the upper wall of the casing.

16. Valve operating mechanism comprising a 5 rocker lever adapted to engage a cam and a valve, a bearing on which said rocker lever is mounted, an axially slideable and rotatably mounted carrier on which the bearing is carried, and regulator means engaging the carrier to automatically 10 maintain it in position holding the rocker lever in engagement with the valve.

17. Valve operating mechanism comprising a 15 rocker lever for operating a valve, said lever having a diametrically slotted hub portion, a cylindrical member mounted to move axially, a bearing in said hub portion and carried by said member, said member extending through the bearing and the slot in the hub portion of the rocker lever, and means engaging the member to 20 regulate the axial position thereof.

18. Valve operating mechanism comprising a 25 rocker lever for operating a valve, said lever having a hub portion with diametric slots therein, a cylindrical member mounted to move axially and having diametric flat portions, and a bearing carried on the member and on which the hub of the lever is mounted, the member extending through the bearing and the slotted portions of the hub and having the flat portions thereof bearing 30 against the hub walls forming one of the slots.

19. In an engine, a casing having a support with spaced ribs, a pin slideable axially and rotatably mounted in the support, a bearing mounted on the pin, a rocker lever fulcrumed on the 35 bearing, and an extension on the rocker lever extending between the ribs of the casing, said ribs and extension being arranged to limit the lateral movement of the rocker lever.

20. Valve operating mechanism comprising a 40 rocker lever for operating a valve, a bearing on which the rocker lever is mounted, carrier means for the bearing movable in a straight line to vary the position thereof, and regulator means engaging the carrier means to automatically position 45 the bearing in a position whereby the lever is maintained in engagement with the valve.

21. Valve operating mechanism comprising a 50 rocker lever having a hub portion, a movable carrier, a bearing carried by the carrier, the hub portion of the lever being mounted on the bearing, and a spring operated cam having an involute peripheral surface directly engaging one end of the carrier.

22. Valve operating mechanism comprising a 55 rocker lever, an axially movable cylindrical carrier member, a bearing carried by the member, said lever being pivotally mounted on the bearing, a cam having an involute peripheral surface engaging one end of the carrier member, and spring 60 means associated to turn the cam relative to the carrier member and thereby maintain the bearing in a desired position.

23. Valve operating mechanism comprising a 65 rocker lever adapted to be rocked to operate a valve, a bearing on which the rocker lever is pivotally mounted, an axially slideable carrier member, and a pressure actuated cam engaging an end of the carrier member, said cam being mounted in alignment with the carrier.

24. Valve operating mechanism comprising a 70 rocker lever adapted to be rocked to operate a valve, a movable fulcrum means for the rocker lever, a cam directly engaging the fulcrum means for regulating its position, a shaft on which said 75 cam is rotatably mounted, a spring housing se-

cured to one side of the cam, a member fixed to the shaft, and a spring in the housing, said spring being secured at one end to the housing and secured at the other end to the member fixed to the shaft, said spring exerting a force to move the cam in a direction shifting the fulcrum means to maintain constant engagement of the rocker lever with the valve. 5

25. Valve operating mechanism comprising a 10 rocker lever adapted to be tripped to operate a valve, a movably mounted fulcrum means for the rocker lever, a cam directly engaging the fulcrum means for regulating its position, a fixed shaft on which the cam is rotatably mounted, a sleeve fixed to the cam adjacent thereto, said sleeve having an arm extending therefrom, a spring housing surrounding the sleeve and having a neck portion fixed to one side of the cam, a coil spring in the housing, one end of the spring being fixed to the sleeve and the other end of the spring being fixed to the housing, said arm being in the path of rotation of the housing neck to limit the rotation of the cam relative to the sleeve. 15 20

26. In a valve operating mechanism, the combination with a cam shaft and a rocker lever operated thereby, of a pivoted carrier for the fulcrum of the rocker lever, a take-up cam operating in contact with, and in offset relation to the axis of, the carrier, and means for vibrating the carrier about its axis. 25 30

27. In a valve take-up mechanism, the combination of a valve operating part, means for adjustably mounting said part to take up clearance, a cam supported by a stationary part with the face of said cam contacting the mounting of said valve operating part to adjust said valve operating part, said mounting means and said cam being separate elements, and a spring having a part connected to the cam for operating said cam. 35 40

28. In an internal combustion engine, the combination with a valve and a rocker arm having a movable support, of a clearance take-up cam mounted on a stationary part of the engine and having a peripheral cam surface in contact with said movable support, said movable support and said cam being separate elements, and means for vibrating said movable support with relation to the cam surface tangent to said surface. 45 50

29. A take-up mechanism comprising two elements, one a cam and the other a sleeve, one of said elements being prepared for pivotal mounting and the other for keyed mounting upon a shaft, a spring having its ends connected to said elements respectively, and stop means between the elements to limit the relative rotary movement thereof, whereby the two elements, the spring and the stop means are self-contained for assembly upon or disassembly from a shaft. 55

30. A take-up mechanism comprising a cam prepared for pivotal mounting, a sleeve prepared for keyed mounting upon a shaft, a coil spring having one end connected to the cam and the other end connected to the sleeve, and stop means between the cam and sleeve to limit the relative rotary movement thereof, whereby the three elements are self-contained for assembly upon or disassembly from a shaft. 60 65

31. The combination with a valve operating means to be adjusted, of an automatic adjusting mechanism including a shaft, a cam rotatably mounted on said shaft to adjust the operating means, a sleeve mounted upon and keyed to said shaft adjacent said cam, a coil spring having one end connected to the cam and the other end 70 75 75

connected to the sleeve, and stop means between the parts to limit the relative rotary movement in both directions between the cam and the sleeve.

32. In a valve operating mechanism, the combination with a support and a cam shaft and a rocker lever mounted on the support and the rocker lever operated by the cam shaft, of a clearance take-up device comprising a spring-operated cam controlling the position of said 10 rocker lever and oscillatively mounted on said support independently of the rocker lever.

33. In an engine valve mechanism, the combination with a cam shaft, a rocker arm having a part in contact with a cam on said shaft and 15 a part for operating a valve, and a valve operated by said rocker arm, of a support for said cam shaft and said rocker arm, means for mounting said rocker arm on said support, said mount-

ing means comprising a bearing which allows the rocker arm to be rocked by the cam shaft to thereby operate the valve, said mounting means being so constructed that the rocker arm may have a slight bodily movement in addition to the 5 rocking action as the cam shaft operates on the rocker arm, and said mounting means providing for adjustment of the rocker arm relative to said support for varying the clearance between the cam shaft and the valve, and spring-actuated 10 cam means directly pivoted upon said support and operating upon said rocker arm in cooperation with the bodily movement thereof caused by the operation of the cam shaft, to adjust the 15 rocking axis of the rocker arm during the operation of the mechanism.

WALTER R. GRISWOLD.
